PIVOTED-LEG COMPASS

Elmer E. Fife, Detroit, Mich.

Application July 26, 1944, Serial No. 546,614

8 Claims. (Cl. 33—27)

1

The invention relates to a two-legged scribing or similar instrument for use in forming circles and arcs whether in ink or pencil, or in the form of a mere scratch.

The principal object of the invention is to provide a novel and effective instrument for accurately scribing circles on steel, particularly small circles, say for $\frac{1}{8}$ " to extremely small ones.

A further object is to provide a novel construction which will insure contact of both legs with the work even if the instrument is not held truly perpendicular to the work.

Another object of the invention is to provide a novel and advantageous construction whereby the pivot leg of the instrument will be held against the work with a much greater pressure component than the scribing leg, to hold said pivot leg against slipping from the proper center point about which an arc or circle is to be described.

Yet another object is to provide a new and improved construction for bracing the scribing leg against twisting and tending to lag behind during operation of the instrument.

A further object is to provide a novel and advantageous quick-acting adjusting means for adjusting the scribing leg toward and from the pivot leg.

A still further object is to provide a comparatively simple and inexpensive instrument, yet one which will be easily operable, reliable and durable.

With the foregoing in view, the invention resides in the novel subject matter hereinafter described and claimed, description being accomplished by reference to the accompanying drawing.

Figure 1 is a side elevation of the instrument, the scribing leg being in the slightly raised position which it occupies before downward pressure is placed upon the operating knob.

Fig. 2 is a vertical sectional view, the scribing leg being lowered to operative position by downward pressure upon the knob.

Figs. 3, 4 and 5 are sectional views as indicated by the correspondingly numbered lines of Fig. 1.

A preferred construction has been illustrated and will be rather specifically described, with the understanding, however, that within the scope of the invention as claimed, variations may be made.

The pivot leg of the instrument is in the form of a vertical shaft 6 having a point 7 at its lower end, said point being by preference adjustably held in an appropriate chuck 8. Slidable upon the upper end of the shaft 6, is an operating knob 9 which is normally held in a raised position by means of a compression spring 10 housed within

the bore 11, which bore also receives the upper end of said shaft 6. A slight distance below the knob 9, the shaft 6 is formed with a diametrical slot 12 for a purpose to appear, and said knob is provided with a downwardly projecting bifurcated lug 13 at one end of said slot, for a purpose which will also later appear.

A sleeve 14 is slidable vertically on the shaft 6 and is by preference provided with bushings 15. At its upper end, the sleeve 14 is formed with two laterally projecting parallel lugs 16 between which the upper end of the scribing leg 17 is pivoted by means of a screw or the like 18. The lower end of this leg is provided with a suitable clamp 19 for holding a scribing point 7a, a pen or a piece of lead. Two parallel arms 20 are formed on the inner edge of the leg 17, said arms straddling the sleeve 14 to brace said leg and prevent it from twisting and lagging during operation of the instrument. In the present disclosure, the sleeve 14 is formed with a hollow lug 21 projecting toward the leg 17, said lug being of rectangular form and having its vertical sides disposed against the arms 20 of said leg 17. The sleeve 14, with its lugs 16 and 21 may well be formed from a single metal blank which may have its meeting edges welded or otherwise joined after being bent to form said sleeve. It is also preferable to form the leg 17 and its arms 20 from a single metal blank which is of such form as to give said leg a channel shape in cross section with its channel disposed toward the leg or shaft 6, said arms 20 being integral with the side flanges 22 of said leg 17.

The inner side of the leg 17 is formed with a curved seat 23, and said leg is also formed with an opening 24 from this seat to the side of said leg remote from the sleeve 14. A block 25, constituting a nut, is rockably engaged with the seat 23, being preferably of cylindrical form. A screw 26, shown as having a left-hand thread, is threaded through the nut 25, the outer end of said screw having an operating knob 27. This screw is of tubular form and its interior is provided with a right-hand screw thread engaging a right-hand screw 28. This screw extends into the hollow boss 21 and is pivoted thereto by a suitable pin or rivet 29.

An elongated yoke 30 which is preferably formed from spring wire, straddles the screw 26 between the side flanges 22 of the scribing leg 17 and bears against the block or nut 25 to hold the latter rockably engaged with the seat 23, the ends of said yoke 30 being secured to said leg 17 by suitable means 31 such as bolts and washers.

By turning the knob 27, in one direction or the

other, it will be seen that the scribing leg 17 will be quickly adjusted inwardly or outwardly as desired, the speed of adjustment being much greater than if only a single screw were provided.

A short lever 32 projects laterally from the leg or shaft 6 and is disposed between the lugs 16 of the sleeve 4, said lever having a rounded inner end 33 received in the slot 12 of said leg or shaft 6. A slot 34 is formed in the outer end of the lever 32 and the screw or the like 18 extends through this slot, to pivotally connect the lever 32 with the sleeve 14. Between its ends, the lever 32 is straddled by the bifurcated lug 13, to which it is pivoted by a pin 35. This pin is relatively close to the inner end 33 of the lever 32 and is relatively distant from the outer end of said lever. This lever, by having its end 33 in the slot 12, is fulcrumed upon the shaft or leg 6, and the parts are so proportioned that the upward thrust on the knob 9, caused by the spring 10, causes the lug 13 to swing said lever upwardly as shown in dotted lines in Fig. 1. The outer end of this lever, being connected with the sleeve 14 by means of a screw or the like 18, thus normally holds said sleeve and the scribing leg 17 in a raised position as seen in Fig. 1. When the instrument is to be used, however, and a downward force is exerted on the knob 9, as indicated by the arrow in Fig. 2, said knob slides downwardly upon the leg or shaft 6, causing the pin 35 to swing the lever 32 downwardly as seen in full lines in said Fig. 2. This downward swing of lever 32 slides the sleeve 14 downwardly upon the leg or shaft 6, and the scribing leg 17 of course moves downwardly with said sleeve until its scribing point or the like 7^a contacts with the surface to be marked. Then, while the instrument is being rotated to mark the work, the downward pressure on the knob 9 is of course continued. This downward force will be split into two components, one acting downwardly on the pivot leg 6 and the other acting downwardly on the scribing leg 17, and due to the location of the pivot 35 near the inner end 33 of the lever 32, the component acting on said pivot leg 6 will be much greater than that acting on the scribing leg 17, with the result that the center point 7 will be effectively held against slippage upon the work. As soon as downward pressure on the knob 9 is relieved, spring 10 again slides said knob upwardly, causing the pivot 34 to restore the lever 32 to its normal raised position and causing said lever to again lift the sleeve 14 and scribing leg 17.

From the foregoing, taken in connection with the accompanying drawing, it will be seen that novel and advantageous provision has been made for carrying out the objects of the invention. Attention is again invited to the possibility of making variations within the scope of the invention as claimed.

I claim:

1. A scribing or similar instrument comprising two legs, an operating knob slidably mounted on one of said legs, and connecting means between said knob and legs including a one-piece lever movable relative to said legs by downward pressure on said knob, said lever being connected at one end to one of said legs, connected at its other end with the other of said legs and connected near said one end with said knob, whereby downward pressure on said knob will result in a relatively strong downward component on said one of said legs and a relatively weak downward component on the other of said legs, said one of said legs having a point at its lower end con-

stituting a pivot for the instrument, said other of said legs having a scribing point.

2. A scribing or similar instrument comprising a vertical shaft having a point at its lower end constituting a pivot for the instrument, a knob slidable vertically on the upper end of said shaft, a sleeve slidable vertically on said shaft under said knob, a leg at one side of said sleeve and having a scribing point at its lower end, means for connecting said leg with said sleeve, a vertically swingable lever extending laterally from said shaft and fulcrumed at its inner end on said shaft, the outer end of said lever being connected with said sleeve to downwardly slide the latter on said shaft when said lever is swung downwardly, and means between the ends of said lever and connecting said lever with said knob for downwardly swinging said lever when said knob is downwardly slid, said means being relatively close to said inner end of said lever and relatively distant from said outer end of said lever to cause said lever to exert a greater downward component on said shaft than on said leg.

3. A scribing or similar instrument comprising a leg having a point at its lower end constituting a pivot for the instrument, a second leg having a scribing point at its lower end, a slideable member on one of said legs, a knob adjacent the upper ends of said legs and slidably mounted on the first mentioned leg, and connecting means between said knob, said slideable member and the upper ends of both of said legs, said connecting means including a one-piece lever pivoted between its ends to said knob and extending transversely with respect to said slideable member and said legs, said lever being movable relative to said legs by downward pressure on said knob.

4. A scribing or similar instrument comprising a vertical shaft having a point at its lower end constituting a pivot for the instrument, a knob slidable vertically on the upper end of said shaft, a sleeve slidable vertically on said shaft under said knob, a leg at one side of said sleeve and having a scribing point at its lower end, means for connecting said leg with said sleeve, a vertically swingable lever extending laterally from said shaft and fulcrumed at its inner end on said shaft, the outer end of said lever being connected with said sleeve to downwardly slide the latter on said shaft when said lever is swung downwardly, and means between the ends of said lever and connecting said lever with said knob for downwardly swinging said lever when said knob is downwardly slid.

5. A structure as specified in claim 2; said means for connecting said leg with said sleeve including a pivot for said leg and a lateral lug on said sleeve through which said leg pivot extends, said leg pivot and lug constituting the means for connecting the outer end of said lever with said sleeve.

6. A scribing or similar instrument comprising two legs, a slideable member on one of said legs, a pivoted connection between the other of said legs and said slideable member, a one-piece lever extending transversely to the longitudinal axes of said legs and having one end fulcrumed to said one of said legs and its other end pivotally connected to said slideable member, and a knob slidably mounted on one of said legs and pivotally connected to the intermediate portion of said lever at a point closer to said one of said legs, whereby downward pressure on said knob will result in a relatively strong downward component on said one of said legs and a relatively

weak downward component on the other of said legs, said one of said legs having a point at its lower end constituting a pivot for the instrument, said other of said legs having a scribing point.

7. In a scribing or similar instrument, a leg having a curved seat in its inner side and an opening from said seat to its outer side, leg-adjusting means including a nut having a curved surface rockably engaging said curved seat and a screw threaded through said nut and extending through said opening, an elongated yoke straddling said screw and extending longitudinally at the inner side of said leg, said yoke bearing between its ends against said nut to hold the latter engaged with said seat, and means securing the ends of said yoke to said leg, said leg being of channel shaped cross section, said nut and yoke being disposed in the channel of said leg.

8. A scribing or similar instrument comprising a leg having a point at its lower end constituting a pivot for the instrument, a knob having a downwardly opening socket to slidably receive the upper end of said leg, a coil spring in said socket above the top of said leg, a sleeve slidable on said leg beneath said knob, a transverse lever fulcrumed at one of its ends to said leg and hav-

ing its other end pivotally connected to said sleeve, the intermediate portion of said lever being pivotally connected to said knob, a second leg having a scribing point at its lower end and its upper end pivotally connected to said sleeve, and a screw-threaded adjusting means between said sleeve and the intermediate portion of said second mentioned leg.
